UNITED STATES PATENT OFFICE.

GEORG HUBER, OF VIENNA, AUSTRIA-HUNGARY, ASSIGNOR OF ONE-HALF
TO SIMON SIMOTTA, OF SAME PLACE.

LUBRICATOR.

SPECIFICATION forming part of Letters Patent No. 616,670, dated December 27, 1898.

Application filed December 29, 1897. Serial No. 664,192. (No model.)

To all whom it may concern:

Be it known that I, GEORG HUBER, a subject of the Emperor of Austria-Hungary, residing in the city of Vienna, in the Province 5 of Lower Austria, in the Empire of Austria-Hungary, have invented certain new and useful Improvements in Lubricators, of which the following is a specification.

The present steam-lubricators for cylinders, sliding valves, governors, &c., are deficient in that the condensing vapor—that is, the water formed thereby—passes through the oil in order to get below the same for the purpose of raising it. The condensed water in 15 passing through the oil heats and soils the same, so that it cannot be used up entirely.

My invention has for its object to avoid the deficiencies above mentioned, and my novel lubricator is so constructed that the condensed vapor enters the oil-receptacle from below, thereby lifting or raising the oil successively without mixing with it and without heating the same, besides insuring the perfect consumption of the oil by means of a suitable oil-discharge conduit provided with a suitable dripping-nozzle, which insures the dripping off of the oil.

My invention is illustrated in the accompanying drawings, in which—
30 Figure 1 is a vertical longitudinal section. Fig. 2 is a vertical cross-section showing partly an elevation of a lubricator as it is mounted directly upon the steam-pipe. Fig. 3 is an elevation, partly in section, showing 35 a modification intended for locomotive-engines which enables the simultaneous lubrication of both engines by a common apparatus; and Figs. 4 and 5 show the drip-nozzles in detail.

40 The apparatus, Figs. 1 and 2, consists of the oil vessel A, provided with a threaded pin a for mounting it upon the steam-pipe. On the top it is closed by a plug b. The lower part of the receptacle, together with plug a, has an axial opening c, not passing entirely 45 through, from which branch off two channels d and f. Below these the opening c is provided with a valve-cone k, actuated by a screw-spindle k', which said cone permits the 50 regulation or stopping of the steam-supply and of the discharge of oil. The one of the

openings d leads to the condensation-pipe g, arranged, preferably, in serpentines about the oil-receptacle A, which pipe embouches into a central channel g, preferably on the opposite portion of the bottom part of the receptacle A. The channel g leads into the oil-chamber and is connected to the same preferably by a short pipe and a stuffing-hose i.

A check-valve m is inserted into the condensation-pipe g. It governs or regulates the supply of steam and does not allow the discharge of the condensing water into the channel d. The check-valve further maintains 65 constantly the pressure within the channel and in the receptacle A. Thus all friction between water and oil is prevented, so that no mixing of these can take place and the oil is pressed out to the last drop.

Alongside of the receptacle A the dripping-pipe h is provided, which communicates on the top with the oil-receptacle A by a channel n, starting right below the lower surface b' of the plug b, and on the lower end by a 75 channel f, with the opening c in the plug a. The discharge of the upper channel is therefore exactly below the upper plug b in order to enable the flowing off of the whole quantity of oil from the receptacle A.

The dripping-pipe h is a sight-glass tightened between the heads h' h' in order to be able to overlook at any time the dripping of the oil. The dripping-nozzle is inserted within the upper head h', whose channel may be 85 closed by the cone-valve p. The nozzle is formed of a small pipe r, the lower end of which is provided with a solid mandrel r', ending in a fine point.

The construction of the dripping-nozzle is 90 shown in detail in Figs. 4 and 5. Fig. 4 shows the mandrel attached in the center of a small pipe, leaving on either side a small exit for the oil. Fig. 5 shows a modification which possesses but one exit for the oil on one side, 95 as is plainly seen from the drawings. The oil supplied to the pipe r by the channel n and the head h' runs down through these openings on the surface of the mandrel and drops off from its point.

100 The function of the apparatus is as follows: Steam from the steam-supply pipe enters

- through bore or channel *c*, channel *d*, and check-valve *m* into the condensing-pipe *g*, from where the condensing-water enters through channel *g'* below the oil-column into the receptacle *A* on its lowest point and thus lifts the oil-column, leading it out drop by drop through channel *n* and valve *p* to the nozzle-pipe *r*, from where the oil passes through the channels *f* and *c* into the valve-box, cylinder, &c. In the same measure as oil drops off from the nozzle steam will enter into the receptacle *A*, whereby constant lubrication is assured. When all the oil in the receptacle *A* is used up, which is the case when 15 pure water drops off in the tube *h*, then the valve *h* is closed, whereupon the water is let off from the receptacle *A* by the cock *s*, and now the receptacle is freshly filled with oil by removing plug *b*.
- 20 For locomotive-engines which require lubrication for two engines I employ a modification of the apparatus, as shown in Fig. 3, provided with two dropping-pipes *h h*, which, however, do not embouch into channel *b*, but 25 communicate with conduits *v v*, leading to the slide-valve boxes. Live steam is admitted directly into the apparatus, which in this instance preferably is attached to the engine-driver stand. In this case the regulating-

valves are arranged, preferably, in a horizontal position, and both drip-pipes *h h* may have either a common feeding-supply channel, as shown in Fig. 3 in dotted lines, or each may have a separate channel *n*.

Having thus described my invention, I claim—

1. A steam-lubricator composed of an oil-receptacle, a steam-condensing pipe provided with a check-valve and communicating with the receptacle at the bottom thus raising the oil by condensed water, a small channel at the top of the receptacle and a drip-nozzle consisting of a small pipe provided with small exits for the oil on its lower end, and a solid mandrel attached thereto and ending in a fine point, substantially as described.

2. In a steam-lubricator an oil-drip nozzle composed of head *h'*, cone-valve *p*, a small pipe *r* provided on its lower end with exit for the oil, a solid mandrel ending in a fine point, and a sight-glass, substantially as described.

In testimony whereof I have signed this specification in presence of two subscribing witnesses.

GEORG HUBER.
